UNITED STATES PATENT OFFICE.

SIEGMUND CHIGER, OF BERLIN, GERMANY.

CHANGE-GIVING APPARATUS.

1,086,510.

Specification of Letters Patent.

Patented Feb. 10, 1914.

Application filed July 24, 1909. Serial No. 509,392.

To all whom it may concern:

Be it known that I, SIEGMUND CHIGER, a subject of the Emperor of Austria-Hungary, residing at No. 65 Kurfürstendamm, Berlin, Germany, have invented a new and useful Change-Giving Apparatus, of which the following is a specification.

My invention has for some of its objects to automatically make change in coins of lower denomination, if coins of the desired higher denomination are not present in the coin-receptacles and allow those coin-ejecting members which contain no coins to remain in their inoperative position; to allow the discharging-devices of the coins of lower denomination to complete their operation without the operation of these of higher denomination being effected; consequently, to diminish the duration of working of the apparatus; to provide drums having projections, and means operated by said drums, whose operation controls the admission of air to the mechanism for ejecting the coins from their cylinders.

In the accompanying drawings, forming part of this specification, Figure 1 is a side view of the machine, Fig. 2 is a vertical sectional view on the line A-B of Fig. 1. Fig. 3 is a vertical sectional view on the line C-D of Fig. 2. Fig. 4 is a plan view of the machine with the casing and mechanism partly removed, showing the interior construction. Fig. 5 is a detail sectional view illustrating the coin-ejecting mechanism drawn to a larger scale. Fig. 5^a is a detail sectional view of a part supplementary to the coin-ejecting mechanism shown in Fig. 5. Fig. 6 is a side view of a part of one coin-ejecting member and of parts for transmitting the adjustment of certain parts in accordance with the amounts contained in the coin-cylinders. Fig. 6^a and Fig. 7 are similar views, in which the parts occupy other positions. Fig. 8 is an elevation of a detail showing scales and figures used for illustrating the principle of transmitting the adjustment of the drums in accordance with the amounts paid and with the price to be paid. Figs. 9 and 10 are elevations of details of the drums. Fig. 11 shows the development of a drum. Figs. 12 and 13 are enlarged vertical sectional

views on the line E-F of Fig. 4 showing parts of the machine in various positions. Fig. 13 is an enlarged sectional view on the line G-H of Fig. 4 showing a detail of the machine. Fig. 14 is a sectional view on the line J-K of Fig. 13. Fig. 16 is a perspective view of a part of the machine. Fig. 17 is a sectional view on the line L-M-N-O of Fig. 3. Fig. 18 is a transverse section on the line P-Q of Fig. 15. Fig. 19 is an elevation of details on a greater scale. Fig. 20 is a transverse section on the line R-S of Fig. 19.

Like parts are indicated by the same letter in all the figures.

Referring to the drawings, 1 is the casing of the apparatus. A shaft 2 passes through the casing 1, and a compressed air reservoir 3 is arranged in the lower portion of said casing. Hollow shafts 4, 5, 6, 7, 7', 7'' are pivotally mounted upon said shaft 2. A disk 8 is mounted on the shaft 2, a disk 9 on the hollow shaft 4, a disk 10 on the hollow shaft 5, a disk 11 on the hollow shaft 6, a disk 12 on the hollow shaft 7. These disks show small circles (Fig. 1), which are distances one from another by one tenth of the circumference of each disk and designated by numbers which form scales. An indicator 13 is arranged on the hollow shaft 4', an indicator 14 is arranged on the hollow shaft 5', an indicator 15 on the hollow shaft 6', an indicator 16 on the hollow shaft 7', an indicator 17 on the hollow shaft 7''. A drum 18 is mounted on the shaft 2, a drum 19 is mounted on the shaft 4, a drum 20 is mounted on the shaft 5, a drum 21 is mounted on the shaft 6. A cog wheel 22 is mounted on the shaft 7, for the purpose of transmitting the movement of the disk 12 to counting wheels not shown in the drawing and adapted to indicate the paper money-pieces each having a value of one hundred marks, for example, in the German currency.

Rows of one and of several projections 23 and 23' are arranged upon the drums 18, 19, 20, 21 in a direction parallel to the axis of the drums. Each row of projections 23 is distanced from the next row of projections 23' by one twentieth of the circumference of a drum. Fig. 12 shows the de-

velopment of a drum provided with rows of projections 23 and 23'.

Fingers 24 and 24' are pivoted to a rod 110 carried by crank-arms 111. The crank-arms 111 are pivoted to a shaft 112 arranged in the casing 1. Each finger 24 and 24' respectively consists of two links, one of which being pivoted at one end to the rod 110, and at the other end pivoted to the second link. 10 The latter can be turned upward toward the other link. The ends of the said fingers rest on rods 25 connected to levers 26 acting on multiple-way taps 27, 42, 43, 44. The tap 27 is adapted to control the passage of compressed air to a cylinder 28. The rod 25 is exposed to the action of a spring 25' endeavoring to bring the rod 25 into the inoperative position, in which a channel 113 of the tap 27 forms a communication between 15 the cylinder 28 and the atmosphere by means of an opening 114.

A piston 29 is arranged in the cylinder 28 and exposed to the action of compressed air controlled by means of the tap 27. The 20 piston is connected by means of a rod 30 with a change-ejecting slide 31. Fig. 5 shows a series of four ejecting-slides 31, 36, 37, 38 arranged the one above the other. Each of the said slides is provided with openings 32, 33, each of which can receive a coin or one of small cases containing paper money. Each ejecting-slide can eject the coin or one of said cases passed into the opening 33 from the corresponding coin-magazine. A 25 movable bottom-plate 34 is arranged beneath the slide 38 and closes the openings of the said ejecting-slides. When the plate 34 is withdrawn, the coin or case filling up one of the openings 32 or 33 falls out of the latter 30 into a channel 34'.

The ejecting-slide 36 is connected to a piston 39, the slide 37 is connected to a piston 40, the slide 38 is connected to a piston 41. The cylinders of the pistons 29, 39, 40, 41 are 45 arranged one above the other, and have compressed-air passages, in which the taps 42, 43 and 44 respectively are arranged. The taps 27, 42, 43, 44 are provided with passages 115 adapted to communicate the cylinders of the pistons 29, 39, 40, 41 with the tube 116 in which one of the taps 117 adapted to regulate the pressure of the air-flow is inserted and which leads compressed air from the reservoir to the taps 27, 42, 43 44.

50 A spring 35 tends to return the ejecting-slides in their inoperative position and to force the slide 38 against the slides 37, 36, 31. Each drum is secured to one toothed wheel 45 provided with ten teeth. A pawl 118 55 and pawls 46 and 47 can engage in each toothed wheel 45. The pawls 46 are mounted loose and the pawls 47 are keyed on a shaft 48 and staggered to each other through half a tooth on engaging in the corresponding wheel 45. The pawls 46 are each pro-

vided with noses 49, the underside of which can be engaged by a lever 51. The levers 51 are pivoted at 50 and provided with pins 52. Each pin projects into a slot 53 or 53' respectively of links 54 and 54'. The links 54 and 54' are connected to one arm of two-arm levers 55 and 55' respectively (Fig. 12 and Fig. 15). To the other arms 57 and 57' of the levers 55 and 55' rods 59 and 59' are pivoted at 58 and 58' respectively. A roller 60 is mounted on the rod 59, and a roller 60' is mounted on the rod 59'. Wedges 62 and 62' each rest with the one side on stationary rollers 61 and 61' respectively, mounted in the casing 1, and with their opposite sides 80 on the rollers 60 and 60' respectively. The wedges 62 and 62' are keyed on rods 63 and 63' respectively. The wedges 62' are provided with a greater pitch than the wedges 62.

The lower end of each rod 59 and 59' is provided with a shoulder 64 and 64' respectively, each of which engages beneath a finger 24 or 24' respectively. Springs 65 tend to return the rods 59 and 59' in their 90 inoperative position. Each pawl 46 is connected by means of a rod 119 with a rod 67, rotatively mounted on a fixed pivot 66. The lower end 68 of each rod 67 engages in the forked end of a rod 69, which is rotatively 95 mounted on a stationary pivot 70 and provided with a cam 71.

A handle-lever 74 having four arms is pivotally mounted at 74' in the casing 1. The arms 74 are provided with openings through 100 which the shafts 2, 4, 5, 6, 7 pass. The lever has an arm 120 (Fig. 16) provided with a handle 121 able to slide in a slot 122 of the said arm and projecting through a slot 123 of the casing 1 out of the latter, for the purpose of being operated by the seller. One of the arms of the lever 74 is provided with an extension 124, which can act on a cam 125 rigidly connected with one of the said crank arms 111. If the lever 74 is in the inoperative position, shown in Fig. 3, then the said extension 124 by means of the cam 125 moves the crank arms 111 against the pressure of a spring 126 and returns the fingers 24, 24' by means of the said crank arms 111 110 and of the rod 110 in their inoperative position out of the path of the projections 23 of the drums.

Levers 75 are pivotally mounted on the shafts of the drums. Each lever 75 carries one of the said pawls 118 pivotally mounted thereon at 127. A coupling-member 76 having nose-shaped projections 128 and 129 is movably arranged in each lever 75. Each coupling-member 76 is provided with a roller 130 and exposed to the action of a spring 78. These springs tend to pull the rollers 130 to the ends of levers 131 pivoted at 132 to the lever 75. A rod 133 is pivoted to each lever 131 and has a forked end in 130

which a roller 134 engages. Each roller 134 is journaled on a rod 135, which is connected at 136 to a pawl 118. One end of the said rod 135 is pivotally mounted on a link 137, 5 pivoted to the corresponding lever 75.

The lever 74 is provided with four recesses 138, each adapted to receive the nose 128 of the corresponding coupling-member 76 for the purpose of coupling the lever 74 with the corresponding lever 75. The engagement of the noses of these coupling-members in the lever 74 is secured by means of guides 79 which are arranged on the casing and along the edges of which the 10 noses 129 slide, which latter by means of the springs 78 are pressed on the guides. The guides 79 are provided with notches 80 and 15 81, in which the noses 129 can engage under certain circumstances.

20 The casing 1 is provided at the top with slots 82 (Fig. 3) for receiving the amount tendered in payment of the purchase made. A channel 83 is arranged beneath each slot 82 and communicates with the same. A 25 shaft 84 rotatively mounted in the casing 1 is keyed to lever-arms 85 to which coin-pushers 86 are connected. An adjustable abutment 88 is arranged in the wall of each channel 83. A movable cam 89 is provided 30 with a slot *b* into which a fixed pin *c* engages and projects into the channel 83 opposite each abutment 88. The coins or the cases containing the paper-money have to slide over the said abutments before passing into the 35 coin-cylinders 91, 92 or 92^a arranged beneath the channel 83. The cam is connected to a link *d* pivotally mounted upon a member *e*. A pawl 94 is pivotally connected to the said cam 89 and to the link *d* (Figs. 19 and 20). 40 For example, if a coin slides over an abutment 88, it will force the cam 89 to slide upon the pin *c* out of its position of rest, and thereby move a pawl 94 pivotally connected to the said cam 89, so as to rotate a 45 spring-ratchet-wheel 90 through one tooth, the said spring-ratchet-wheel 90 is connected with one end of a spring *s* and meshing with a counting-train. The other end of said spring *s* is fixed at *t*. One of such devices is provided for each channel 83 and the coins passing into the coin-cylinders are counted by 50 means of these devices. A flap 93 is arranged above the coin-cylinder 92. This flap can be adjusted from the outside of the 55 casing 1, and in the raised position as shown it will close the top of the coin-cylinder 92, thereby forming a sloping surface along which the inserted coins slide into the cylinder 91. The flap 93 will be turned downward 60 as shown in Fig. 3 in dotted lines, if it is desired, that the coins now pass from the channel 83 into the coin-cylinder 92.

65 Each of the ejecting slides 31, 36, 37, 38 is provided with one tappet 98, which on the outward movement of the slide rocks a

bell-crank lever 96, one arm 97 of which projecting into the path of the corresponding tappet. The tappets 98 are mounted on the vertical arms of the said ejecting-slides so as to pivot only in one direction, and thus 70 on the return of the slides into the initial position slide idly over the lever-arms 97. Each lever 96 is pivoted to a rod 95 connected at its other end 99 to a lever 100, pivotally mounted on the casing 1. The free end of each lever 100 acts on a nose of a 75 detent 101 which engages in the teeth of the spring-ratchet-wheel 90 stopping it. On the lever 96 being pivoted by means of the tappet 98, each lever 100 will be moved downward and thus disengage the detent 101 from its corresponding spring ratchet-wheel 90, so that the latter will run back by the action of its spring to the extent of one tooth, the ratchet-wheel being again directly 80 locked in position by the detent engaging with the next tooth.

Each ratchet-wheel 90 is attached to an axle 139 (Figs. 3, 17). Some axles 139 have keyed thereon disks 103. Other axles 139 have keyed thereon disks 103'. Each of the said disks 103 and 103' has four teeth, which can engage in a toothed segment 104 or 104' respectively, which are pivotally mounted at 105. Each of the latter has also 95 four teeth. Each toothed sector 104 is coupled to one arm of a two-armed lever 106, the other arm of which is pivotally connected to the rod 63. Each toothed sector 104' is coupled to one arm of a two-armed lever 106', the other arm of which is pivotally connected to a rod 63'. Fig. 3 shows the disk 103 meshing with the sector 104. When the ejecting-slides 31 and 36 are pushed forward out of the position shown in Fig. 3, the tappets operate the detent by means of the levers 96 and 100, so that the ratchet-wheel 90 runs back turning by means of the disk 103 the sector 104 toward the left into its zero position and will move the wedge 62 connected to the rod 63 into its upper position. The disks 103 and 103' mesh with the sectors 104 and 104' respectively and the latter enter their zero position on the 100 failure of the corresponding coin-cylinders 91. In the construction, illustrated in the drawings, the cylinders 92 and 92^a are out 105 of function.

110 Each ejecting slide shown in the drawings can when operated eject only one coin out of the said cylinder 91. As the wheel 90 has ten teeth, the same will make one revolution, if ten coins pass the abutment 88 and form the charge of the cylinder 91. Therefore, the wheel 90 will make one revolution in the opposite direction, if ten coins are ejected by means of the ejecting slides from the coin-cylinder 91. Each coin-cylinder 91 should contain never more than nine 115 coins, so that the wheel 90 passes its zero 120 125 130

position only when the coin-cylinder is empty.

Primary coin-cylinders 91 cause the actuation of disks 103. Additional coin-cylinders 91 are provided, governing disks 103', which cylinders are only brought into use on the failure of certain of the primary coin-cylinders. The hubs 140 of the levers 75 pivoting on the shafts of the drums are connected with springs 141 (Figs. 12 and 15), each arranged in a recess of the corresponding tooth wheel 45, and the other ends of which springs are each connected to the said wheel. These springs constantly tend to return the drums into their zero position. The return of the drums into the zero position is effected in the direction opposite to the hands of a clock and after the disengaging of the pawls 46, 47 and 118, as may be seen from the following: The pawls 46 are each provided with a wedge-shaped side tappet 142. Four springs 143 having two points are secured to the lever 74 (Fig. 16) for actuating the said tappets 142. On turning the lever 74 in the direction of the hands of a clock (Fig. 15) each spring slides along the side wedge surface of the tappet 142 of the corresponding pawl 46 without affecting the latter, as shown in Figs. 15 and 18. On the return movement, however, of the lever 74, in the opposite direction to that of the hands of a clock, the points of the springs 143 are so pressed against the tappets 142 that the pawls 46 are disengaged from the toothed wheels 45, as may be seen from Figs. 15 and 18 showing the pawls in dotted lines. Each pawl 47 is provided with an arm 144 having a pin 145 projecting into the path of the nose 49 of the pawl 46 and adapted to be operated by turning the pawl 46 in the direction opposite to that of the hands of a clock. For the purpose of showing the principle according to which this device changes, reference is made to Fig. 10. A rotary disk 8 is arranged concentrically to the fixed scale 9, and the rotary disk 8 is also provided with a scale. The divisions of both scales are equal one to the other, and the figures indicating them run in the same direction. The scale 8 is for the amount tendered, the fixed scale 9 for the amount to be paid. If, for example, a client has tendered 5 marks and has only to pay 3 marks, then the seller moves the rotary disk 8 in the direction of the arrow, until its division 3 corresponds with the division 5 of the scale 9. At this moment, the rotary disk has been moved over two divisions. This movement of the slide can be used for moving the drums into their operative position.

Instead of a rotary disk 8 a slide S referring to a modification and (Fig. 9) provided with a scale in combination with a fixed scale A is employed, as may be seen from Fig. 8. The slide S is used for the indica-

tion of the amount tendered and the fixed scale A for the indication of the amount to be paid. If, for example, the amount to be paid amounts to 3 marks and the customer has tendered 5 marks, the coin paid will be inserted in its corresponding slot 82. Then the indicator 14 is moved along the disk 10 situated in the zero position, until the indicator corresponds with the figure 5 of the said disk. The disk 10 is turned in the direction of the hands of a clock, until the figure 3 of the disk is situated opposite the indicator 14. This relative displacement of the disk 10 with respect to the indicator has a result that the drum 20 is turned and a projection 23 of the same will pass into the operative position, in which it is held by the pawl 46, which engages in the teeth of the corresponding toothed wheel 45, in a position opposite that of the finger 24 adapted to control the operation of an ejecting slide which is able to eject one coin of the value of two marks. Now, the lever 74 is turned in the direction of the hands of a clock out of the position of rest I shown in dotted lines in Fig. 12. The lever 74, carrying along with it the levers 75, causes the drum 20 to be turned by means of the pawl 118, whereby the levers 75 come into the operative position II shown in dotted lines in Fig. 12, and the fingers 24 are moved under the action of the spring 126 into the path of the projections 23. In this position of the levers 75, the nose 129 of each coupling-member 76 has reached the notch 80. The noses engage in the notches and stop the levers 75, while the noses 128 are moved out of the recesses 138 of the lever 74 and release the same. In this position the levers 75 remain standing. By turning the drums one projection 23 has been pushed against the finger 24 which forms a member of the two-marks-coins ejecting-device. The projection 23 will press down by means of the said finger 24 the rod 25 connected to the compressed-air tap 44 (Fig. 3) and makes the latter to communicate the cylinder of the piston 41 with the compressed-air reservoir 3. The compressed air will pass into the said cylinder and move the piston 41 forward, so that the ejecting slide 38 delivers one two-marks-coin. After the delivery of change required the lever 74 is first turned farther in the direction of the hands of a clock, until the right points of the springs 143 have snapped behind the tappets 142 of the pawls 46. Then the lever 74 is moved downward, whereby the springs 143 turn the pawls 46 and 47 and 118 into the position indicated in dotted lines in Fig. 15. The rod 67 will be turned to the left shown in dotted lines in Fig. 15, and the cam 71 will draw the rod 133 and the arm 131 as well as the coupling-member 76 to the left and move the nose 129 out of the 180

notch 80, while the nose 128 again engages in the recess 138 of the lever 74 and couples the latter with the lever 75. By this operation of all the coupling-members all the 5 levers 75 are coupled with the lever 74, whereupon by means of the latter the levers 75 are again turned opposite the direction of the hands of a clock into the position of rest.

The above-mentioned operation can only 10 be effected, when the ejecting-slide which is to be operated is charged with one two-marks piece out of the coin-cylinder 91. On the failure of the said coin-cylinder 91, then the device will operate in the following 15 manner: It has been already mentioned above that by means of the parts 95, 96, 97, 98, 90, 103, 104, 106 the corresponding wedge 62 will be raised, when the corresponding coin-cylinder 91 contains no coins. 20 On the failure of the primary coin-cylinder arranged for receiving two-marks coins the corresponding wedge 62 is raised. The said wedge forces when raised as shown in dotted lines in Fig. 12 the roller 60 to the right and 25 turns the rod 59 around the pivot 58, so that the lower shoulder 64 will pass to the left beneath the finger 24 and raise the latter from the rod 25. This action of the rod 59 will prevent the finger 24 to drive the rod 30 25 into its operative position and to cause an operation of the ejector for the cylinder carrying two marks. Now, if the lever 74 is turned in the direction of the hands of a clock out of the position I into the position 35 II (Fig. 12), then the drum 20 will be turned by means of the pawl 118, the projection 23 will strike against the finger 24, press the latter downward and carry the rod 59 along with it. This rod 59 will turn 40 consequently the lever 55, so that the link 54 and with it the lever 51 is raised. The said lever will turn the pawl 46 by means of the lug 49 out of the teeth of the toothed wheel 45, whereby the rod 67 is turned into 45 that position (indicated in dotted lines in Fig. 12), in which the cam 71 operated by the said rod 67 will press by means of the roller 134 the rod 133, the arm 131 and the coupling-member 76 to the left, for the purpose of preventing the nose 129 to engage 50 in the notch 80. By continuing the movement of the lever 74 in the direction of the hands of a clock the cam 71 will make the pawl 118 to be disengaged from the toothed wheel 45. In this disengagement-position 55 of the pawls 46 and 118, the drum 20 will rotate back under the action of its spring 141 but be soon stopped by the pawl 47 as shown in Fig. 15. On this return movement 60 of the drum, the finger 24 is released from the projection 23. The rod 59 will return into its position of rest by the action of its spring 65, the parts 51, 46, 67, 69, 71 will return into their position of rest and 65 two projections 23' will pass into their opera-

tive position above two fingers 24'. The said fingers 24' form members of the one-mark ejecting-device. The lever 74 is turned farther above the notch 80 in the direction of the hands of a clock, whereby the pawl 118 70 will carry the drum along with it, and the said two projections 23' will press down on the said two fingers 24', until the nose 129 has arrived at the notch 81. If two one-mark-coins are present in the primary coin-cylinders 91, the corresponding wedge 62' 75 is set in the lower position and the rods 59' remain in their position of rest and the nose 129 can snap in the notch 81 for locking the lever 75 in its operative position, whereby the fingers 24' are pressed down on two rods 25 connected with the taps 43 and 44 respectively, which will communicate the cylinders of the pistons 40 and 41, which when operated will actuate the one-mark ejecting-slides 37 and 38, with the compressed-air reservoir 3.

After the delivery of the two one-mark coins, the lever 74 is first turned farther in the direction of the hands of the clock, until the left points of the springs 143 have glided off from the tappets 142 (Fig. 15). Then the lever 74 is turned in the opposite direction, thereby drawing the pawls 46, 47 and 118 into the position shown in dotted lines in Fig. 15, so as to release the drum 20, which then will rotate under the action of its return spring 141 into its initial position on the hub 140. The taps 43 and 44 will be drawn into their inoperative position, in 90 which their channels 113 communicate the cylinders of the pistons 40 and 41 with the openings 114, through which the compressed air can escape out of the said cylinders, so that the spring 35 will press the pistons 40 and 41 into their initial position.

If sufficient one-mark coins are not present in the additional coin-cylinders 91, the corresponding wedge 62' has been raised by means of the ratchet-wheel 90, disk 103', toothed sector 104' and rod 63'. The wedge 62' will turn the rod 59' and move the shoulder 64' of the same into the operative position near the ends of the fingers 24' as shown in Fig. 15. By turning the lever 74 in the direction of the hands of a clock above the notch 81 the projections 23' will pull the fingers 24' and by means of the latter the rod 59' down, which will turn the lever 55' and elevate the link 54' and the lever 51 into the position shown in dotted lines in Fig. 15. The lever 51 will turn the pawl 46 against the pin 145 connected to the pawl 47 and move the said pawls 46 and 47 in the position shown in dotted lines in Fig. 15. The rod 67 will be swung far to the left and the cam 71 brought into a position, in which it forces the rod 133, link 137, pawl 118 and arm 131 into the position shown in dotted lines, which position will prevent un- 115 120 125 130

coupling of the lever 74 from the levers 75 and the nose 129 from engaging in the notch 81. All the pawls 46, 47, and 118 are disengaged from the toothed wheels 43, so that 5 all the drums are released and under the action of their return-springs rotate back into their initial position, and the levers 74 and 75 can be moved back into their position of rest. On moving back the lever 74, 10 the springs 143 actuate the tappets 142 of the pawls 46 and turn the latter into the position shown in dotted lines in Fig. 15 and prevent the noses from snapping in the notches 80 and the levers 75 from being 15 locked, so as to allow their return-movement. Consequently, the drums 18, 19, 20, 21 and the disks 8, 9, 10, 11 connected thereto will rotate back in their zero position. The five-marks coin thrown into the channel 83 will 20 be pushed by turning the shaft 84 and the coin-pusher 86 into the corresponding coin-cylinder 91. The coins ejected by the ejecting slides 31, 36, 37, 38 pass into a trough 107 (Fig. 3, 5*).

25 I claim:

1. In a change-returning apparatus, the combination of drums provided with projections, with fingers movably arranged opposite the said drums, a delivering mechanism controlled by the said fingers and drums, operating means for operating the said drums, coin-receptacles, disengaging-means whereby the said drums when operated on the failure of certain of the said 30 coin-receptacles are disengaged from the said operating means, toothed wheels each provided with ten teeth and secured to one of the said drums and operated by the said operating means, pairs of pawls rotatably 35 mounted on a pivot, one pawl of each pair connected with the said disengaging-means standing back with its free end through a half tooth-division on the said toothed wheel's periphery as compared with the other pawl, all substantially as set forth.

2. In a change-returning apparatus, the combination of drums provided with projections, with fingers movably arranged opposite the said drums, a delivering mechanism controlled by the said fingers and drums, toothed wheels each of which is secured to one of the said drums, operating levers carrying pawls adapted to engage in the said toothed wheels and to operate the 40 said drums, disengaging-means whereby the said pawls when operated on the failure of certain of the coin-receptacles to operate the said drums for delivering coins out of the said coin-receptacles are disengaged from 45 the said toothed wheels, all substantially as set forth.

3. In a change-returning apparatus, the combination of drums provided with projections, with fingers movably arranged opposite the said drums, a delivering mechanism

controlled by the said fingers and drums, operating means for operating the said drums, rods adapted to throw the said operating means out of gear and provided with shoulders projecting when in the operative 70 position into the path of the said fingers, coin-receptacles, wedges actuating the said rods and adapted to move the same into the operative position, and means for drawing the said wedges into the operative position 75 on the failure of certain of the said coin-receptacles, all substantially as set forth.

4. In a change-returning apparatus, the combination of drums provided with projections, with fingers movably arranged opposite the said drums, a delivering mechanism controlled by the said fingers and drums, toothed wheels each of which is secured to one of the said drums, operating levers each of which carries a pawl adapted to engage 80 in one of the said toothed wheels and to operate the corresponding drum, a handle-lever having recesses, a coupling-member arranged in each of the said operating levers, a spring able to press a coupling-member 85 against a curved guide, notches arranged in the said guide, two noses arranged on each coupling-member, one of the said noses sliding on a guide and adapted to snap in the said notches under the action of the said 90 spring, the other of the said noses projecting into the said recesses for coupling the said handle-lever with the operating levers, all substantially as set forth.

5. In a change-returning apparatus, the 100 combination of drums, with fingers movably arranged opposite the said drums, a delivering mechanism controlled by the said fingers and drums, toothed wheels each of which is secured to one of the said drums, operating 105 levers each of which carries a pawl adapted to engage in one of the said toothed wheels and to operate the corresponding drum, a coupling-member arranged in each of the said operating levers and spring-pressed 110 against a curved guide, coin receptacles, disengaging-means whereby the said pawl when operated in order to operate the drums and to deliver coins on the failure of the corresponding coin-receptacles is disengaged from 115 the corresponding toothed wheel, and an arm rotatably mounted on each operating lever connected to the said disengaging-means and actuating the said coupling-member, all substantially as set forth.

6. In a change-returning apparatus, the combination of drums provided with projections, with fingers movably arranged opposite the said drums, and a delivering mechanism controlled by the said fingers and drums, toothed wheels secured to the said drums, operating levers for operating the said drums and carrying operating-pawls engaging in the said toothed wheels, pairs 125 of pawls rotatably mounted on a pivot, one 130

pawl of each pair connected with a cam whereby the said pawl when disengaged from the said corresponding toothed wheel will actuate the corresponding operating-
5 pawl to allow the drum connected to the said toothed wheel to rotate back, all substantially as set forth.

In testimony whereof I have hereunto affixed my signature in presence of two witnesses.

SIEGMUND CHIGER.
